CLAIM

I claim the ornamental design for an end cap, as shown and described.

DESCRIPTION

FIG. 1 is a back/bottom/left perspective view of a first embodiment of the new design, shown broken in the center with a double line to indicate that no particular length is claimed.

FIG. 2 is a top view of the design shown in FIG. 1. The bottom view is identical to the top view.

FIG. 3 is a left side view of the design shown in FIG. 1. The right side view is the mirror image of the left side view.

FIG. 4 is a front view of the design shown in FIG. 1.

FIG. 5 is a back view of the design shown in FIG. 1.

FIG. 6 is a back/bottom/left perspective view of a second embodiment of the new design, shown broken in the center with a double line to indicate that no particular length is claimed.

FIG. 7 is a top view of the design shown in FIG. 5. The bottom view is identical to the top view.

FIG. 8 is a left side view of the design shown in FIG. 5. The right side view is the mirror image of the left side view.

FIG. 9 is a front view of the design shown in FIG. 5; and, FIG. 10 is a back view of the design shown in FIG. 5.

The double lines shown in FIGS. 1 and 6 form no part of the claimed design. In addition, the shading lines shown in all of the drawings represent the approximate three-dimensional contour of the design, and thus are not intended to indicate surface decoration.
